DESIGN FOR A COMBINATION LAMP SOCKET AND EJECTOR

Morris Schwartz, New York, and William
Castedello, Huntington, N. Y.

Application May 22, 1940, Serial No. 92,592

Term of patent 14 years

To all whom it may concern:

Be it known that we, Morris Schwartz and William Castedello, citizens of the United States, residing in New York city, in the county of New York, and in Huntington, county of Suffolk, respectively, and State of New York, have invented a new, original, and ornamental Design for a Combination Lamp Socket and Ejector, of which the following is a specification, reference being had to the accompanying drawing, forming part thereof.

Fig. 1 is a front elevational view of a combina-

tion lamp socket and ejector showing our new design.

Fig. 2 is a side elevational view, and
Fig. 3 is a top plan view thereof.

The dominant features of our design reside in the portion shown in full lines in the drawing.

We claim:

The ornamental design for a combination lamp socket and ejector, substantially as shown and described.

MORRIS SCHWARTZ.
